UNITED STATES PATENT OFFICE.

OTTMAR H. KOPP, OF BROOKLYN, NEW YORK, ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

Application filed April 1, 1925. Serial No. 19,759.

The present invention relates to a telephone system in which connections are established by means of automatic switches.

In the case of power driven apparatus, 5 register senders are employed to control the extension of connections. Heretofore it has been customary if the apparatus failed to function correctly and did not complete selections within a specified time, that a signal 10 was transmitted to an operator who then released the connection. Also, if the subscriber abandoned the call before the completion of the connection, the apparatus operated to inform the operator, who would 15 then release the sender and apparatus associated with the subscriber's line.

It is an object of the present invention to provide means for automatically releasing the register sender if a call is not completed 20 within a reasonable time.

A feature of the invention lies in means for opening the connection between the district selector and the register sender in order to dismiss the sender.

25 Another feature of the invention lies in a timing switch for insuring a predetermined interval before causing the dismissal of the sender.

Another feature of the invention lies in means for providing a longer time interval 30 before the dismissal of the sender in the case of outgoing calls to mechanical offices.

An additional feature of the invention lies in means for preventing the wipe out of 35 calls to manual offices and the signaling of a monitoring operator during any desired period of the day.

A further feature of the invention lies in the restarting of the timing switch at the 40 beginning of the successive stages of the extension of a connection.

Still another feature of the invention lies in the provision of means to inform a monitor operator of the stage of the establishment 45 of a connection which was unduly delayed.

This arrangement has been disclosed in connection with a sender suitable for use in tandem offices such as disclosed in Patent No. 1,501,871 to F. A. Stearn, issued July 15, 50 1924.

This disclosure is similar to that of application Serial No. 19,584, filed March 31, 1925, in the name of L. H. Johnson and T. H.

Roberts and similar reference numerals have, therefore, been applied to parts corresponding to those in the above identified application. Certain portions of the disclosure not essential to an understanding of the present invention have been indicated by dotted rectangles, as will be clear from the following 55 description. For a full description of the complete circuit reference may be had to such application.

Referring now to the drawings, Fig. 1 shows in diagrammatic form a subscriber's 60 line with selectors for extending said lines and a sender for controlling such selector's.

Fig. 2 shows a district selector at a tandem office.

Fig. 3 shows an outgoing selector at the 70 tandem office, the incoming and final selector at a third office, and call indicator apparatus at still another office.

Fig. 4 shows a link circuit for associating the sender and the district-selector of Fig. 2.

Fig. 5 shows a timing switch and means for controlling the wiping out of an uncompleted call.

Fig. 6 shows the means for receiving code impulses from the distant office and the 80 transfer relays for directing the registration of said impulses.

Fig. 7 shows the counting relays and sequence switch for controlling selections.

Fig. 8 shows a sequence switch and apparatus for controlling the selection and setting 85 of a translator.

Fig. 9 shows the class switch and the relay call indicator impulse generating switch.

Fig. 10 shows the arrangement of Figs. 1 90 to 9, inclusive, in order to make a complete disclosure of the invention.

Call to full mechanical office.

Assume that the subscriber at substation 95 100, located at office X, desires to talk to a subscriber at substation 380 located at office Z, which may be reached only through the tandem office Y. The subscriber dials the number of the wanted line. The line 100 will 100 be extended by means of line switch 101 to district selector 102. The number dialed will be registered on sender 104 and that sender will control district selector 102 and office selector 103 to select trunk 249—250 leading 105 to tandem district selector 200 at the tandem

office Y. For a description of the registration of the wanted number on the sender and the action of said sender in controlling the extension to an outgoing trunk reference 5 may be made to U. S. Patent 1,395,977 to F. A. Stearn, et al., granted November 1, 1921, and for a description of the method of sending code pulses reference may be made to Patent 1,464,084, to A. E. Lundell 10 et al., issued August 7, 1923.

When office selector 103 connects with trunk 249—250, a relay (not shown) at sender 104 will be bridged across conductors 249 and 250, completing a circuit for relay 201 which 15 may be traced from battery at the outer left back contact of relay 234, right winding of relay 201, lower left contact of cam 203, upper back contact of relay 202, over trunk conductor 249, through office selector 103, 20 and district selector 102, through the above mentioned relay in the sender 104, back through district selector 102 and office selector 103, trunk conductor 250, inner lower back contact of relay 202, lower right 25 contact of cam 204, left winding of relay 201, inner right back contact of relay 234 to ground. The operation of relay 201 closes a circuit from battery through the winding of relay 205, lower right contact of cam 206, 30 outer left back contact of relay 207, lower contacts of cam 208, front contact of relay 201 to ground. When relay 205 operates it closes a circuit from ground at its inner left front contact over the upper right and lower 35 left contacts of cam 209, conductor 405 and thence through apparatus (not shown) to relay 400 associated with allotter switch 410. The allotter switch shown in detail in the 40 above mentioned application of L. H. Johnson, et al., is represented by the rectangle at the lower left corner of Fig. 4. Relay 400 closes a circuit (not shown) for operating relay 408. Relay 408 operates and 45 closes a circuit from battery through the winding of relay 503, left back contact of relay 502, contact of jack 501, conductor 411, contact of relay 408 to ground. Relay 503 in operating locks over its inner right contact, right back contact of relay 502, conductor 504 to ground at the contact of relay 400. Relay 503 in operating also closes a 50 circuit from battery, through the winding of relay 505, inner left contact of relay 503 to ground. The circuits closed by the operation of relay 505 will be discussed later.

Relay 503 also closes a circuit from battery through the winding of start magnet 510, back contact of stop magnet 511, outer left contact of relay 503 to ground. The power driven switch 500 is rotated under the control of magnet 510 until brush 512 engages the terminal connected to the district selector 200, which terminal is connected with ground, thus closing a circuit from battery, 60 through the winding of relay 508, and from

battery through the winding of stop magnet 511 and back contact of relay 518, in parallel, over the outer right contact of relay 503, brush 512, and the terminal corresponding to selector 200, conductor 509, lower contacts 70 of cam 212, outer left front contact of relay 205, right contact of cam 213 to ground.

It will be noted that in the case of a district selector which has not been selected for use relay 205 will not be operated and the 75 path from ground will not be extended to the terminals of finder switches. Relay 508 and magnet 511 operate in the above traced circuit, magnet 511 serving to open the circuit of magnet 510, bringing the switch 500 80 to rest on the terminals leading to selector 200. Relay 508 closes a circuit from battery through the winding of relay 518, outer right front contact of relay 508 to ground. Relay 518 operates and closes a locking circuit for itself over its inner right contact, left winding of relay 519, brush 513 to conductor 528, from whence the circuit is extended to ground as will be subsequently described. Relay 518 also closes an obvious 90 circuit for relay 502, closes a holding circuit for magnet 511 at its inner left alternate contact, and closes a new holding circuit for relay 503 which extends over the inner right contact of relay 503, inner right front contact of relay 508, outer left contact of relay 518, outer left front contact of relay 503 to ground.

The operation of relay 502 opens the first traced locking circuit for relay 503, closes a holding circuit for relay 505 at its middle right contact, and closes a circuit from battery through the left winding of relay 207, upper left and lower right contacts of cam 214, conductor 529, brush 514 and its corresponding terminal, left front contact of relay 502, left contact of relay 508 to ground. Relay 207 operates and locks over its outer left front contact, lower contacts of cam 208, to ground at the front contact of relay 201. The operation of relay 207 opens the circuit of relay 205 which relay releases, opening the circuit of relay 400. Relay 207 also connects ground from the front contact of relay 201, lower contacts of cam 208, right front contact of relay 207, lower contacts of cam 215, non-inductive resistance 216, to conductor 528, completing the locking circuit of relay 518, which was previously traced to conductor 528. Relay 519 being marginal 110 does not operate through resistance 216.

Relay 207 also closes a circuit from battery through the winding of sequence switch magnet 210, upper left contact of cam 217, inner left front contact of relay 207, upper left and lower right contacts of cam 218, back contact of relay 205, right contact of cam 213 to ground, advancing sequence switch 210 to position 3.

In position 2 of sequence switch 210 the 130

locking circuit of relay 518 is extended over the upper right contact of cam 219 to ground, where it is maintained until sequence switch 210 leaves position 13. The release of relay 205 as previously described also removes ground from conductor 509, thus opening the circuit of relay 508.

The release of relay 508 opens the locking circuit of relay 503 and that relay also releases. When sequence switch 210 reaches position 3, the circuit of relay 201 is extended from battery, outer left back contact of relay 234, right winding of relay 201, right contacts of cam 218, left back contact of relay 205, lower right and upper left contacts of cam 203, conductor 249, and thence as previously traced to conductor 250, left contacts of cam 204, right back contact of relay 205, left winding of relay 201, right back contact of relay 234 to ground, so that relay 201 is maintained energized.

In the meantime the operation of relay 505 as previously described closes a circuit from battery through the winding of relay 530, right back contact of relay 531, outer right front contact of relay 505 to ground. Relay 530 operates and locks over its right front contact, back contact of stop magnet 521, outer right contact of relay 505 to ground. It also closes a circuit from battery through the winding of allotter magnet 410, left contact of cam 413, conductor 532, contact of jack 501, left contact of relay 505 to ground, advancing allotter 410 to position 2 in which position it is ready to allot another link circuit for use in connection with a subsequent call.

The operation of relay 530 closes a circuit from battery through the winding of relay 531, inner left front contact of relay 530 to ground at the outer right contact of relay 505. Relay 531 closes a circuit from battery through the start magnet 520, which controls the operation of switch 550, outer right front contact of relay 531, right front contact of relay 530, back contact of magnet 521, outer right front contact of relay 505 to ground. It also opens the energizing circuit of relay 530. Switch 550 is then rotated under the control of magnet 520 until it engages an idle sender which is characterized by battery through a resistance connected to conductor 601. When an idle sender is reached, a circuit is closed from battery, inner back contact of relay 701, resistance 700, conductor 601, terminal served by brush 522, corresponding to the idle sender, inner right contact of relay 505, both windings of relay 533, winding of relay 534, outer right contact of relay 505 to ground. Relay 533 operates and short circuits its high resistance winding permitting marginal relay 534 to operate. The operation of relay 534 closes a circuit from battery through stop magnet 521, contact of

relay 534, outer right contact of relay 505 to ground.

Magnet 521 operates and opens the locking circuit of relay 530 and the energizing circuit for magnet 520. Relay 530 and magnet 520 release. Relay 530 on releasing closes a holding circuit for magnet 521 over the inner left front contact of relay 531, right back contact of relay 530, outer right contact of relay 505 to ground. This circuit is in shunt of the windings of relays 533, and 534 so that these relays also release. With relays 530 and 508 released and relays 502 and 531 operated a circuit is closed from battery through the winding of relay 535, outer right front contact of relay 502, outer left back contact of relay 530, outer left contact of relay 531, right back contact of relay 508 to ground. Relay 535 in operating extends the fundamental tip and ring conductors and certain control conductors from the district selector to the sender. It also closes a circuit from ground through resistance 536, brush 523 and its corresponding bank terminal, conductor 602, left winding of relay 603, outer left back contact of relay 701, winding of relay 702 to battery. Relay 702 operates, but relay 603 being marginal does not. Relay 702 locks to its energizing circuit independent of the contact of relay 701.

Relay 702 also closes an obvious energizing circuit for relay 701 which in operating removes battery from conductor 601 to mark the sender busy to other link circuits. The operation of relay 535 also closes a circuit from battery, through the winding of relay 205, lower contacts of cam 214, conductor 529, brush 514 and the terminal served thereby, right winding of relay 519, inner left contact of relay 535, brush 524 and its corresponding terminal, right winding of relay 603, left back contact of relay 604, right back contact of relay 703, inner left front contact of relay 702 to ground. Relays 519 and 603 being differential the completion of this circuit does not cause the operation of either relay. Relay 205 operates and connects the trunk conductors 249 and 250 through to the pulsing relays of the sender, disconnecting them from the windings of relay 201. This relay releases and releases relay 207.

Relay 702 in operating also closes a circuit from battery, through the winding of relay 605, No. 1 terminal and brush 614 of timing switch 600, left back contact of relay 606, conductor 607, upper left contact of cam 1000, upper left contact of relay 1001, conductor 1002, outer right contact of relay 702 to ground. Relay 605 operates and locks to its energizing circuit independent of the timing switch. The purpose and operation of this timing switch will be more completely discussed later.

The pulsing circuit extends from sender 104 through the district and office selectors, conductor 249, upper left and lower right contacts of cam 203, outer left front contact of relay 205, lower right contact of cam 212, upper left contact of cam 221, conductor 538, brush 516, middle right contact of relay 535, brush 526, conductor 619, inner left back contact of relay 703, right back contact of relay 704, winding of marginal relay 705, winding of negatively polarized relay 706, winding of positively polarized relay 707, inner left back contact of relay 704, left contacts of cam 900, conductor 618, brush 525, inner right contact of relay 535, brush 515, conductor 537, lower contacts of cam 220, outer right front contact of relay 205, left contacts of cam 204, conductor 250 and thence through the office and district 20 selectors to the sender 104.

The completion of this circuit, due to the operation of relay 205, initiates certain operations at the sender 104 which result in the transmission of code impulses to correspond to the number of the wanted line. For a description of these operations reference may be made to the above mentioned Patent No. 1,464,084 to A. E. Lundell, et al., issued August 7, 1923.

30 The code impulses consist of light and heavy negative pulses and positive pulses. The light negative pulses cause the operation of relay 706, the heavy negative pulses the operation of relays 706 and 705, and the positive pulses the operation of relay 707. The operations of relay 706 serve to control a cycle of operations of relays 708 and 709, which in turn control the operation of the pairs of transfer relays 710, 711, etc. A 40 pair of transfer relays is operated in response to the code pulses representing each digit. The operation of relay 705 or relay 707 causes the operation of certain relays in the registers indicated by rectangle 800, according to which set of transfer relays have last been operated. For the operation of the transfer relays and of the register relays of rectangle 800 reference may be made to the above mentioned application of L. H. Johnson, et al. When relay 716 operates, after 50 the reception of the station's pulses, as described in the above identified application, a circuit is closed from battery, through the winding of sequence switch magnet 1010, lower right contact of cam 1004, outer left back contact of relay 1005, outer left front contact of relay 716 to ground, advancing switch 1010 to position 2. When 55 the last code impulse has been received and relay 704 operates, a circuit is closed from battery, through the winding of relay 703, outer right front contact of relay 704 to ground. Relay 703 operates and locks over its inner right front contact to ground 60 at the inner left front contact of relay 702.

The operation of relay 703 opens the fundamental circuit, preventing the reception of any further pulses.

The operation of relay 703 opens the circuit of relay 205 which relay releases and again extends the trunk conductors 249 and 250 to the windings of relay 201. District selector 102 now completes a loop over the trunk conductors whereupon relay 201 is again operated. The operation of relay 201 70 closes a circuit from battery through the winding of relay 222, left contact of cam 203, outer left back contact of relay 207, lower contacts of cam 208, front contact of relay 201 to ground. Relay 222 operates 75 and locks over its left front contact and the lower left contact of cam 223 to ground at the upper left contact of cam 223 through position $3\frac{1}{2}$ of sequence switch 210 and then in positions $3\frac{3}{4}$ to 7 to ground over the 80 lower right contact of cam 223 and the front contact of relay 201. The operation of relay 222 closes a circuit from battery through the winding of sequence switch magnet 210, left contact of cam 224, inner left back contact of relay 207, right front contact of relay 222 to ground advancing the sequence switch to position 4.

As soon as switch 1010 reaches position $1\frac{3}{4}$ ground is connected over the lower left contact of cam 1006 to conductor 880, which is extended by means of registers 800 to control the setting of secondary registers, which are indicated by rectangle 1100. When these secondary registers are positioned, a circuit is closed over the lower left contact of cam 1004 to advance sequence switch 1010 to position 4. In accordance with the position taken by secondary registers 1100, one of the relays 1007, 1011, 1012 100 or 1013 is operated to cause a translator 105 finder to select a translator and connect it with the sender. The translator finders and translators are indicated diagrammatically by the rectangle 1050. The translator is positioned by means of revertive impulses, in a manner similar to the selection of a subscriber's line by a final selector. For a complete description of the selection of a translator and the positioning of the same, reference 110 may be made to the above identified application of L. H. Johnson, et al. Sequence switch 1010 is advanced from position to position as the translator is set and when the translator comes to rest on the terminals selected by the positioning of registers 1100, switch 1010 will be in position 11. As soon as switch 1010 reaches position 10, a circuit is closed for relay 1027 over the lower left contact of cam 1024, which connects the 120 translator to the tertiary registers represented by rectangle 1300. The tertiary registers 1300 are then set under the control of the translator. When they have been completely set, sequence switch 1010 is advanced 125 130

to position 12. As soon as switch 1010 leaves position 11, the translator finder and the translator are disconnected from the sender.

When the registers 1300 have been positioned circuits are completed for positioning class switch 1200, in accordance with the class of call to be extended. Switch 1200 sets up the proper conditions for completing the call and also selects the proper stepping relay and testing resistance to be included in the fundamental circuit according to the resistance of the trunk over which such fundamental circuit extends. Rectangles 1300 and 1300^A represent the same set of registers, but have been separated for convenience of drawing.

Relay 1202 is energized in parallel with sequence switch 1200 and releases when the switch comes to rest to close a circuit from ground over its back contact, conductor 1032, upper left contact of cam 1031, conductor 727, outer right front contact of relay 703, conductor 728, lower left contact of cam 920, winding of sequence switch magnet 910 to battery, advancing this sequence switch to position 2.

With sequence switch 910 in position 2 a circuit is completed from battery through the winding of sequence switch magnet 1010, lower right contact of cam 1025, lower left contact of cam 921 to ground, advancing sequence switch 1010 to position 13.

With sequence switch 1010 in position 13 and sequence switch 910 in position 2 the fundamental circuit is completed from battery through the left winding of relay 207, left contacts of cam 221, conductor 538, brush 516, middle right contact of relay 535, brush 526, conductor 619, upper left contact of cam 1019, conductor 1020, lower contact of cam 901, back contact of relay 902, winding of relay 903, winding of relay 904, lower left contact of cam 1201, (assuming switch 1200 is now in position 8 to correspond to a call to a mechanical office), contact of cam 1021, lower contact of cam 906, resistance 907 to ground. Relays 904 and 207 operate in this circuit.

Relay 207 locks over its outer left front contact, upper left contact of cam 212, upper left contact of cam 221, to conductor 538 and thence over the fundamental circuit as traced to ground. The operation of relay 207 closes a circuit from battery through the winding of sequence switch magnet 210, upper left contact of cam 217, inner left front contact of relay 207, front contact of relay 222 to ground. Sequence switch 210 advances in this circuit to position 5. In position 5 the energizing circuit of relay 207 is opened but the locking circuit is maintained closed. A circuit is completed for updrive magnet 225 over the upper right and lower left contacts of cam 226, inner left front contact of relay 207, right front contact of

relay 222 to ground. As the brush rod moves upward an intermittent circuit is completed from battery, left winding of relay 207, outer left front contact of relay 207, upper left contact of cam 212, upper left contact 70 of cam 221, lower left and upper right contacts of cam 227, commutator strip 228, brush 229, lower left contact of cam 219 to ground.

Relay 904 closes a circuit from battery at 75 the inner left contact of relay 701, conductor 622, through one of the counting relays over one of the conductors 913, 919, 922, 908 or 934, through contacts of the registers shown at 1300^A over the upper right and 80 lower left contacts of cam 950, upper right contact of cam 1000, lower left contact of cam 1001, conductor 1023, upper right and lower left contacts of cam 909, front contact of relay 904, lower left contact of cam 911 to 85 ground.

The counting relays operate in the usual manner, locking through the winding of the corresponding prime counting relay. When the above traced intermittent circuit is 90 closed, relay 904 is shunted and the prime counting relay operates. Each time that the intermittent circuit is completed a pair of counting relays lock up to extend the circuit to the next pair of counting relays. 95 When this circuit has been completed a sufficient number of times, relays 915 and 902 are operated in the locking circuit of the No. 0 counting relay, which may be traced from battery at the left front contact of relay 701, conductor 622, winding of the No. 0 counting relay, windings of relays 902 and 915 in parallel, front contact of the No. 0 counting relay, upper left contact of cam 925 to ground. Relay 902 serves to open 105 the fundamental circuit permitting the release of relay 207. Relay 915 closes a circuit from battery through the winding of sequence switch magnet 910, upper right contact of cam 924, inner right back contact of relay 918, front contact of relay 915 to ground, advancing the sequence switch 910 to position 4. In passing from position 110 2 to position 4 sequence switch 910 opens the locking circuit of the counting relays 115 and they release.

The release of relay 207 opens the circuit of updrive magnet 225, bringing the selector 200 to rest. Relay 207 in releasing closes a circuit from battery through the winding 120 of sequence switch magnet 210, lower left contact of cam 224, inner left back contact of relay 207, contact of relay 222 to ground advancing the sequence switch to position 6.

When sequence switch 210 is in position 125 6 and sequence switch 910 in position 4 the fundamental circuit is again established. Relay 207 operates and locks as above and advances sequence switch 210 to position 7 in which position the energizing circuit of 130

relay 207 is opened but the locking circuit is maintained. As soon as sequence switch 210 reaches position 6 a circuit is completed through trip magnet 230, lower right contact of cam 219 to ground. In position 7 the circuit of updrive magnet 225 is again established over the upper right and lower left contacts of cam 226, inner left front contact of relay 207 to ground at the front contact of relay 222. Relay 904 in operating closes the usual counting relay circuit, including the registers of 1300A.

An intermittent circuit is completed through the left winding of relay 207, outer left front contact of relay 207, upper contacts of cam 212, commutator strip 231, brush 232, lower left contact of cam 219 to ground. As before, this circuit is completed each time that brush 232 encounters a conducting segment of strip 231. The completion of this circuit causes the operation and locking of a pair of counting relays in the usual manner. When it has been completed a sufficient number of times relays 902 and 915 operate in the locking circuit of the No. 0 counting relay, which is the same as previously traced. Relay 902 opens the fundamental circuit to release relay 207 and relay 915 operates to advance sequence switch 910 to position 5.

The release of relay 207 opens the circuit of updrive magnet 225, bringing the switch to rest with the brushes upon the first terminals of the desired group of outgoing trunks. At its inner left back contact relay 207 closes a circuit for advancing sequence switch 210 to position 8. With sequence switch 210 in position 8, relay 207 is operated in a local circuit extending from battery, through its right winding, lower contacts of cam 233, inner left back contact of relay 234, right front contact of relay 222 to ground. Relay 207 operates and locks in a circuit from battery, through its left winding and outer left and right front contacts, lower left and upper right contacts of cam 215, to sleeve brush 235 provided that the first trunk of the group is busy.

The operation of relay 207 also closes a circuit from battery through the winding of sequence switch magnet 210, upper left contact of cam 217, inner left front contact of relay 207, to ground at the right front contact of relay 222, advancing sequence switch 210 to position 9. If the first trunk of the group is idle relay 207 releases immediately that the sequence switch leaves position 8 1/4. Should the first trunk be busy, however, relay 207 is held operated to close a circuit through updrive magnet 225 extending over the upper right and lower left contacts of cam 226, inner left front contact of relay 207, front contact of relay 222 to ground. Switch 200 will be advanced 65 under the control of the updrive magnet in

search of an idle trunk. Relay 207 is maintained energized between terminals by means of a circuit through its right winding, lower left and upper right contacts of cam 233, centering commutator strip 286, brush 287, left contacts of cam 226, inner left front contact of relay 207 to ground at the front contact of relay 222.

When brush 235 encounters an idle outgoing trunk, relay 207 is released as soon as its brushes are properly centered and the holding circuit through the centering strip 286 is broken. As soon as relay 207 releases the circuit of updrive magnet 225 is opened, and a circuit is completed from battery 80 through the winding of sequence switch magnet 210, lower left contact of cam 224, inner left back contact of relay 207 to ground at the front contact of relay 222 to advance the sequence switch to position 10. 85 As soon as relay 207 releases, it connects ground from the upper right contact of cam 206, over its outer left back contact, right contacts of cam 208, to the sleeve brush 235 to mark the terminal busy. When sequence 90 switch 210 arrives in position 10 ground is connected to brush 235 over the upper contacts of cam 208, independent of relay 207.

In position 10 of sequence switch 210, direct ground from relay 222 over the left contacts of cam 218 is connected in shunt of the ground through resistance 216 to conductor 528, and thence over brush 513, through the left winding of relay 519, front contact and winding of relay 518 to battery. 100 Relay 519 now receives sufficient current to cause it to operate. It connects direct ground from its front contact over brush 523, conductor 602, left winding of relay 603 to the front contact and winding of relay 702. Relay 603 now receives sufficient current to cause it to operate and it closes a circuit from battery through the winding of sequence switch magnet 910, lower left contact of cam 924, front contact of relay 603 110 to ground, advancing sequence switch 910 to position 6.

With sequence switch 910 in position 6 a circuit is closed from battery through the left winding of relay 207, upper left and lower right contacts of cam 214, conductor 529, brush 514, right winding of relay 519, inner left contact of relay 535, brush 524, right winding of relay 603, back contact of relay 604, back contact of relay 623, lower 120 left contact of cam 925 to ground. Relay 207 operates in this circuit and closes a circuit from battery through magnet 210, upper left contact of cam 217, inner left front contact of relay 207, front contact of relay 222 125 to ground advancing the sequence switch to position 11. In this position subsequent selections take place and the fundamental circuit from the sender is connected through to the office selector of Fig. 3. When se- 130

quence switch 210 leaves position 10 the direct ground is removed from conductor 528, leaving only the ground through resistance 216. Since relay 519 is differential

5 the circuit just traced for relay 207 now causes relay 519 to release. The release of relay 519 removes direct ground from the winding of relay 603 so that, since relay 603 is also differentially wound, the above 10 traced circuit for relay 207 causes the release of relay 603 as well.

The fundamental circuit is now closed for testing the office selector. A circuit is closed from battery, through the left winding of relay 301, lower left contact of cam 302, lower left contact of cam 303, district selector brush 236, lower contacts of cam 227, conductor 538, brush 516, middle contact of relay 535, brush 526, conductor 619, 20 upper left contact of cam 1019, conductor 1020, lower contact of cam 901, back contact of relay 902, winding of relay 903, contact of cam 1205, winding of relay 926, resistances 1206 and 1207, lower contact of cam 25 927, upper left and lower right contacts of cam 928, right back contact of relay 1033, lower right contact of cam 950, upper left contact of cam 900, conductor 618, brush 525, inner right contact of relay 535, brush 515, conductor 537, right contacts of cam 220, district selector brush 237, resistance 352, left contacts of cam 353 to ground.

If the office selector and relay 301 in that selector are in normal condition the above 35 traced circuit is completed and relay 926 operates but relay 301 does not. The operation of relay 926 closes an obvious circuit for relay 929, which in turn closes a circuit for relay 930. Relay 930 in operating locks 40 through its inner right front contact, upper contact of cam 1208, lower right contact of cam 931 to ground. The operation of relay 930 closes a circuit from battery through the winding of magnet 910, lower left contact of cam 932, lower right contact of cam 1209, left front contact of relay 930, outer right back contact of relay 936 to ground, advancing sequence switch 910 to position 8. As soon as switch 910 leaves position 6 the

50 circuit of relay 926 is opened and that relay releases, in turn releasing relay 929. The locking circuit of relay 930 is also opened permitting that relay to release. When switch 910 reaches position 8 the fundamental circuit extends from conductor 619, upper left contact of cam 1019, conductor 1020, lower contact of cam 901, back contact of relay 902, winding of relay 903, winding of relay 904, left contact of cam 1201, left 55 contact of cam 933, left contact of cam 1034 to conductor 618 and thence as traced to ground at cam 353. This circuit does not include resistances 1206 and 1207 and hence relay 301 operates therein. If relay 301

should operate falsely in the test circuit previously traced it would advance sequence switch 310 to position 2 and block the reestablishment of the fundamental circuit. 65

The operation of relay 301 in the fundamental circuit traced in position 8 of sequence switch 910 closes a circuit from battery, through the winding of magnet 310, lower left contact of cam 304, outer left front contact of relay 301 to ground, advancing the sequence switch to position 2. 70 75 The energizing circuit of relay 301 is opened at this time but a locking circuit extending over its inner and middle left front contacts, and the upper left contact of cam 302, closed while sequence switch 310 is still in position 80 1, is maintained in position 2 holding relay 301 operated. With sequence switch 310 in position 2 a circuit is closed from battery, through the winding of updrive magnet 305, right contacts of cam 306, outer left front 85 contact of relay 301 to ground advancing the selector 300 in its brush selecting operation.

Relay 904 also operates in this fundamental circuit and closes the usual counting 90 relay circuit. As selector 300 moves upward a circuit is intermittently closed through the left winding of relay 301, inner and middle left front contacts of relay 301, upper left and lower right contacts of cam 95 302, commutator strip 307, brush 308, lower left contact of cam 353 to ground. This circuit serves to hold relay 301 operated and to shunt relay 904 causing that relay to release. This results in the operation and 100 locking of successive pairs of counting relays.

When sufficient pairs of counting relays have been operated, relays 902 and 915 operate in the locking circuit of the No. 0 counting relay and relay 301 releases. The operation of relay 915 closes a circuit from battery, through the winding of sequence switch 910, upper right contact of cam 924, inner right back contact of relay 918, front contact of relay 915 to ground, advancing that sequence switch to position 10 and releasing the counting relays. 105 110

The release of relay 301 opens the circuit of updrive magnet 305, bringing the switch 115 to rest in position to trip the desired set of brushes. It also closes a circuit from battery, winding of sequence switch magnet 310, upper left contact of cam 304, outer left back contact of relay 301 to ground advancing sequence switch 310 to position 3. As soon as the sequence switch reaches position 3 a circuit is established for trip magnet 318 over the upper right contact of cam 315 to ground, so that when switch 300 is again moved upward the desired set of brushes will be tripped. 120 125

With switch 910 in position 10 and switch

310 in position 3 the fundamental circuit is again established as described and relays 301 and 904 operate as before. Relay 301 locks and closes the previously traced circuit for advancing sequence switch 310 to position 4. In position 4 the locking circuit of relay 301 is maintained and the previously traced circuit for updrive magnet 305 reestablished. Relay 904 in operating closes the usual counting relay circuit. As switch 300 moves upward, brush 311 completes an intermittent circuit through the left winding of relay 301 and its inner and middle front contacts, upper contacts of cam 302, commutator strip 309, brush 311, lower left contact of cam 353 to ground.

When this intermittent circuit has been completed a sufficient number of times, relays 915 and 902 operate in the locking circuit of the No. 0 counting relay. Relay 902 as before, opens the fundamental circuit permitting the relay 301 to release as soon as brush 311 leaves the conducting segment of strip 309. Relay 915 closes the usual circuit to advance sequence switch 910 to position 12.

Relay 301 releasing advances sequence switch 310 to position 5. In position 5 relay 301 is disconnected from the fundamental circuit and is operated in a local circuit through its right winding and left contacts of cam 312 to ground. Relay 301 locks over its inner front contact, lower contacts of cam 313 to sleeve brush 314, assuming that the first outgoing trunk is busy. The operation of relay 301 advances the sequence switch 310 to position 6, in which position the circuit of the updrive magnet is again closed to advance the selector 300 in search of an idle outgoing trunk. Relay 301 is held operated between terminals by means of a circuit through its right winding, upper contacts of cam 312, centering commutator strip 320, brush 308, right contact of cam 353, outer front contact of relay 301 to ground. When switch 300 encounters an idle outgoing trunk no ground will appear on the terminal engaged by brush 314 and the locking circuit of relay 301 is opened. The energizing circuit of relay 301 is opened as soon as sequence switch 310 reaches position 6 and the holding circuit is opened as soon as the brush set is properly centered. Relay 301 in releasing closes a circuit from battery through the winding of sequence switch 310, upper left contact of cam 304, outer back contact of relay 301 to ground, advancing sequence switch 310 to position 7. The release of relay 301 also opens the circuit of updrive magnet 305 so that the brushes come to rest on the selected trunk.

As soon as relay 301 releases, it connects ground over its inner left back contact, lower contacts of cam 313, to brush 314 to mark

the selected trunk busy to other outgoing selectors. As soon as sequence switch 310 reaches position 6½ ground is connected to sleeve 314 over the left contact of cam 315, maintaining the busy condition as long as switch 300 is in use.

In position 7 relay 301 is operated through its right winding, left contacts of cam 312 to ground and locks over its inner and middle front contacts, left contacts of cam 316, sleeve conductor 321, district sleeve brush 235, upper contacts of cam 208 to ground. Relay 301 also advances sequence switch 310 to position 8. Switch 310 remains in position 8 and relay 301 remains locked throughout the progress of the call.

When switch 910 reached position 11 in passing to position 12 it closed a circuit from battery through the winding of sequence switch 1010, upper right contact of cam 1017, right contact of cam 921 to ground, advancing sequence switch 1010 to position 14. When switch 1010 reaches position 14 it completes an additional holding circuit for relay 207 which extends from the back contact of relay 623, over the lower contact of cam 1031, conductor 1032 to the back contact of relay 1202. This holds relay 207 operated while switch 910 passes through the first part of its second revolution.

In position 12 of switch 910 relay 926 is again connected across the outgoing trunk, the circuit extending at this time from conductor 619, upper left contact of cam 1019, conductor 1020, lower contact of cam 901, back contact of relay 902, relay 903, contact of cam 1205, winding of relay 926, resistances 1206 and 1207, lower contact of cam 927, upper left and lower right contacts of cam 928, lower contact of cam 1034 to conductor 618. It may be noted that in the positions of sequence switch 1200 corresponding to routes of high resistances, resistance 1207 is short circuited to equalize the resistance in the circuit of relay 926. If the incoming selector is in position to receive a call relay 926 operates as before, in turn operating relays 929 and 930. Relay 930 locks over its inner right front contact, upper contact of cam 1208, lower right contact of cam 931 to ground. Relay 930 also closes a shunt around the contacts of cam 928, holding relay 926 operated until switch 910 leaves position 14. Relay 930 also closes a circuit for advancing sequence switch 910 to position 1 extending from battery through the winding of magnet 910, lower left contact of cam 932, lower right contact of cam 1209, left front contact of relay 930, outer right back contact of relay 936 to ground. When sequence switch 910 leaves position 18 relay 930 releases. Sequence switch 910 is then advanced to position 2 on its second revolution in a circuit through its winding,

lower left contact of cam 920, conductor 728, outer right front contact of relay 703, conductor 727, upper left contact of cam 1031, conductor 1032, back contact of relay 1202 to ground.

With switch 910 in position 2 sequence switch 1010 is advanced to position 15, in a circuit from battery through the winding of sequence switch magnet 1010, lower contact of cam 1025, lower left contact of cam 921 to ground. When switch 1010 reaches position 15, relay 1033 is operated in a circuit through its winding, upper left contact of cam 1024 to ground. With sequence switch 910 in position 2 and switch 1010 in position 15 the fundamental circuit is established from the incoming selector at station Z over the tip brush 317 of office selector 300, lower contacts of cam 303, district selector brush 236, lower contacts of cam 227, conductor 538, brush 516, middle right contact of relay 535, brush 526, conductor 619, upper left contact of cam 1019, lower contact of cam 901, back contact of relay 902, winding of relay 903, winding of relay 904, lower left contact of cam 1201, right contact of cam 933, resistance 937, upper right contact of cam 1034, conductor 618, brush 525, inner contact of relay 535, brush 515, conductor 537, right contacts of cam 220, district selector brush 237, upper contacts of cam 313, brush 319 of office selector 300 to the incoming selector.

The stepping relay 904 functions in the same manner as for district selections. When sufficient pulses are received from the incoming selector, relays 902 and 915 operate as usual, advancing the incoming selector sequence switch and advancing sequence switch 910 to position 4.

In position 4 the fundamental circuit is again established for incoming group selection. When sufficient pulses have been received relays 902 and 915 operate advancing the incoming selector and advancing sequence switch 910 to position 5. The incoming selector proceeds to hunt for an idle final selector in the well known manner. When such a final selector has been found the incoming selector advances and extends the fundamental circuit to the final selector. Sequence switch 910 is advanced from position 5 over a circuit through its winding and the lower left contact of cam 924, to ground on the inner left contact of relay 1033.

With sequence switch 910 in position 6 the fundamental circuit is again established from the final selector for final brush selection. When sufficient impulses have been received relays 902 and 915 operate to advance the final selector sequence switch and to advance sequence switch 910 to position 8.

In position 8 the fundamental circuit is again established, this time for final group

selection. When sufficient pulses have been received, relays 902 and 915 operate. As before, relay 902 causes the advance of the final selector sequence switch and relay 915 causes the advance of sequence switch 910 to position 10.

Final units selection takes place when sequence switch 910 is in position 10. When sufficient pulses have been received relays 902 and 915 operate as before and advance the final selector sequence switch and sequence switch 910 to position 12. The final selector proceeds to test the called line and, assuming it to be idle, advances the incoming selector to a position in which battery is connected to the ring conductor and ground to the tip conductor thus reversing the direction of current flow over the fundamental circuit which in position 12 of switch 910 extends from conductor 619 over the upper left contact of cam 1019, conductor 1020, lower contact of cam 901, back contact of relay 902, winding of relay 903, winding of relay 904, left contact of cam 1201, right contact of cam 933, resistance 937, upper right contact of cam 1034 to conductor 618. The current at this time is in the direction to cause relay 903 to operate. At its front contact relay 903 closes a circuit in parallel through the windings of relays 940 and 918. Relays 918 and 940 operate, relay 940 closing a locking circuit for the two relays over its front contact, upper left contact of cam 911 to ground.

Relay 904 also operates. With relays 918 and 904 both operated a circuit is closed from battery through the winding of the No. 0 counting relay, lower contact of cam 941, middle left contact of relay 918, upper contacts of cam 909, front contact of relay 904, left contact of cam 911 to ground. The No. 0 counting relay operates and locks as usual. The closure of the fundamental circuit as above traced causes the incoming selector sequence switch to advance, opening the fundamental circuit, releasing relays 903 and 904 and permitting relays 902 and 915 to operate.

Relay 915 closes a circuit from battery through the winding of magnet 910, lower right contact of cam 924, inner right contact of relay 936, right front contact of relay 918, front contact of relay 915 to ground, advancing the sequence switch to position 13, from which position it is advanced to position 15 by means of a circuit through its winding, upper right contact of cam 932, upper contact of cam 1036, inner left contact of relay 918 to ground. Sequence switch 910 is then advanced to position 16 in a circuit through its winding, upper left contact of cam 920, back contact of relay 603 to ground.

When switch 910 reaches position 16 a circuit is completed from battery, through the winding of relay 604, lower contact of

cam 1037, lower right contact of cam 911 to ground. The operation of relay 604 opens the circuit through the right windings of relays 603 and 519 and the left winding of relay 207. Relay 207 releases, closing a circuit from battery through the winding of magnet 210, left contact of cam 224, inner left back contact of relay 207, front contact of relay 222 to ground, advancing sequence switch 210 to position 12. With switch 210 in position 12, direct ground is connected from the front contact of relay 222 over the left contacts of cam 218 to the left winding of relay 519, causing that relay to operate. Relay 519 in operating connects direct ground to the left winding of relay 603 causing it to operate. With sequence switch 210 in position 12, relay 207 reoperates in a circuit from battery through its left winding, lower contacts of cam 221, lower left contact of cam 219 to ground. The operation of relay 207 closes the usual circuit for advancing sequence switch 210 to position 13 in which position relay 207 releases. Sequence switch 210 is advanced to position 14 in a circuit from battery, winding of magnet 210, upper right contact of cam 217, lower right contact of cam 224, inner left back contact of relay 207 to ground at the front contact of relay 222, and to position 15 in a similar circuit over the lower right contact of cam 217 and upper right contact of cam 224.

When switch 210 leaves position 13 ground is removed from conductor 528, opening the circuit through the left winding of relay 519, initiating the disconnection of the sender which will be described later.

When the called subscriber answers, battery and ground are connected to the talking conductors at the distant office operating relay 238 in a circuit extending over the tip conductor through the upper winding of relay 238, resistance 239, lower contacts of cam 240, lower winding of relay 238, and thence over the ring conductor. Relay 238 operates and closes a circuit from battery, through the left winding of relay 207, upper contacts of cam 214, front contact of relay 238 to ground. The operation of relay 207 advances sequence switch 210 to position 16. Relay 207 releases as switch 210 passes from position 15 to position 16, but reoperates in the latter position, through its right winding, lower contacts of cam 233, inner left back contact of relay 234, to ground at the front contact of relay 222. The reoperation of relay 207 advances switch 210 to position 17.

When switch 210 reaches position 15 $\frac{3}{4}$ a circuit is closed from battery, winding of relay 202, upper left and lower right contacts of cam 233, inner left back contact of relay 234, front contact of relay 222 to ground. Relay 202 in operating extends the talking conductors through tandem office Y to office

Z. The operation of relay 202 also disconnects relay 201 from the talking conductors and closes a local circuit for holding that relay operated from battery, outer left back contact of relay 234, right winding of relay 201, lower left contact of cam 203, lower front contact of relay 202, front contact of relay 238 to ground. The bridged resistance 239 is maintained across the talking conductors until the sequence switch leaves position 16. Conversation takes place in position 17 of the district selector sequence switch.

When ground is removed from conductor 528 as previously mentioned, relay 519 releases opening the circuit through the left winding of relay 603, and the winding of relay 702. Relays 603 and 702 release. With relay 702 released a circuit is closed from battery, winding of sequence switch 85 magnet 1010, upper left contact of cam 1017, left back contact of relay 702 to ground. This circuit advances sequence switch 1010 to position 16.

When sequence switch 1010 leaves position 15 the locking circuit of relay 703 is opened as well as the circuit of relay 1033. A circuit is then closed from battery, winding of sequence switch magnet 910, lower right contact of cam 920, upper left contact of cam 1029 to ground, in which circuit sequence switch 910 is advanced to position 17. On reaching position 17 the circuit of relay 604 and the locking circuit of relay 940 are opened, the release of relay 940 releasing relay 918. With relay 918 normal, a circuit is closed from battery, winding of magnet 910, upper left contact of cam 924, outer right back contact of relay 918 to ground advancing the sequence switch to position 18. Sequence switch 910 is then advanced to position 1 in a circuit over the lower right contact of cam 920, upper left contact of cam 1029 to ground. Relay 701 is held operated over conductor 729, as long as either sequence switch 1010 or 910 is off normal, the circuit extending to ground either at the upper left contact of cam 1006 or at the lower right contact of cam 925. Sequence switch 1010 is advanced from position 16 to position 17 in a circuit over the lower left contact of cam 1017, right back contact of relay 1005 to ground, and from position 17 to position 18 over the upper right contact of cam 1004, upper contact of cam 921 to ground. When sequence switch 910 has reached position 1, if impulse sequence switch 1210 is also in position 1, a circuit is closed for advancing switch 1010 to position 1 over the upper left contact of cam 1004, conductor 1038, left contacts of cam 1211, conductor 1212, upper left and lower right contacts of cam 943 to ground.

With both sequence switches 910 and 1010 in position 1 relay 701 is released connect.

ing battery through resistance 700 to the terminal of brush 522 indicating that the sender is normal and ready to receive further calls.

5 The removal of ground from the left winding of relay 519 also causes the release of relay 518. Relay 518 in turn releases relay 502 and stop magnet 511. Relay 502 in turn releases relay 505 and relay 505 releases relay 531. The release of relay 531 opens the circuit of stop magnet 521. The release of relay 502 also opens the circuit of relay 535 disconnecting the sender finder from the district finder and this circuit is now normal.

When the called subscriber hangs up his receiver, relay 238 releases in turn releasing relay 207. Relay 238 also opens the holding circuit of relay 201 and that relay 20 releases, in turn releasing relay 222. When relay 222 closes its back contact a circuit is completed from battery through the winding of magnet 210, upper right and lower left contact of cam 241, left back contact 25 of relay 205, lower contacts of cam 242, back contact of relay 222 to ground. Sequence switch 210 is advanced to position 18 in this circuit. In position 18, the circuit of downdrive magnet 243 is closed over 30 the lower contacts of cam 241, left back contact of relay 205, lower contacts of cam 242 to ground at the back contact of relay 222. The district selector 200 is restored to normal under the control of downdrive magnet 243. When the brushes take up their

normal position a circuit is closed from battery through the winding of sequence switch magnet 210, lower left contact of cam 217, commutator segment 244, brush 287, lower 40 left contact of cam 219 to ground, restoring the district selector to normal.

When switch 210 leaves position 17½ ground is removed from brush 235 and the holding circuit of relay 301 is opened. 45 When relay 301 closes its back contact it closes a circuit from battery through the winding of magnet 310, upper left contact of cam 304, outer back contact of relay 301 to ground, in which circuit sequence switch 50 310 is advanced to position 18. In position 18 the circuit of downdrive magnet 322 is closed over the lower contacts of cam 312 and selector 300 is restored to normal. When the brush set reaches its normal position a circuit is closed from battery through magnet 310, upper left contact of cam 304, commutator segment 323, brush 308, lower left contact of cam 353 to ground 55 restoring the switch 310 to position 1 at which time the circuit is in condition for further calls.

Call to a manual office.

In the case of calls to a manual office

equipped with relay call indicator apparatus, the connection will progress as described for a mechanical call through office group selections except that the class switch will be set in position 1, 3, 5, or any odd position. When sequence switch 1010 reaches position 65 13 at the beginning of district selections a circuit is closed from battery through the windings of relay 1214, contacts of cam 1215, conductor 1243, right contact of cam 1031, conductor 1032, back contact of relay 1202 70 to ground. Relay 1214 locks through position 1 to 17 of switch 1210 over its front contact, upper contact of cam 1216, conductor 1217, upper right contact of cam 1029 to ground. The operation of relay 1214 also 80 closes a circuit from battery, winding of sequence switch magnet 1210, lower right contact of cam 1218, lower right and upper left contacts of cam 1219, outer right front contact of relay 1214 to ground. This circuit 85 starts switch 1210 out of position 1 and it is advanced in its rotation to position 12 by means of its master cam. When switch 1210 reaches position 2 a circuit is closed from battery through the winding of relay 1220, 90 lower left and upper right contacts of cam 1221, outer right front contact of relay 1214 to ground. Relay 1220 operates and locks over its inner left front contact, lower contact of cam 1216, conductor 1217, upper left 95 contact of cam 1029 to ground as soon as switch 1210 reaches position 10. This locking circuit is closed in positions 10 to 2 of switch 1210.

When sequence switch 910 reaches positions 11 and 12 after the completion of office group selections a circuit is closed as previously described for advancing switch 1010 to position 14. With switch 910 in position 100 12 and sequence switch 1010 in position 14 relay 926 is bridged across the trunk conductors in the manner previously described, except that switch 1200 is set for relay call indicator operation and a shunt is closed around resistances 1206 and 1207 from the contact of cam 1213 over the upper contact of cam 927. Relay 926 operates in this circuit and causes the operation of relays 929 and 930 as before. Relay 930 operates and locks over the lower right contact of cam 110 1208, upper right contact of cam 931 to ground. As before the operation of relay 930 closes a shunt around the contacts of cam 928, holding relay 926 operated in positions 115 13 and 14. It also closes a circuit from battery, winding of sequence switch magnet 910, lower right contact of cam 932, left contact of cam 1209, inner left front contact of relay 930, outer right back contact of relay 936 to ground, advancing switch 910 to position 13. 120 Sequence switch 1210 at this time has arrived in position 12 and a circuit is completed from battery, winding of magnet 910, 125

upper right contact of cam 920, right contact of cam 1222, right contact of cam 1223 to ground, advancing switch 910 to position 14.

5 The connection of relay 926 across the trunk lights a lamp at the call indicator operator's position at office Z'. When this operator closes her display key, relay 926 is released, in turn releasing relays 929 and 930. With relay 930 released, sequence switch 910 in position 14, sequence switch 1010 in position 14 and class sequence switch 1200 in an odd position, say 5, the tip conductor from the relay call indicator office extending to conductor 619 is continued over the upper contacts of cam 1019, left contacts of relay 939, outer left back contact of relay 930, conductor 1282 to cams 1225 and 1224 of switch 1210. The ring conductor in turn, which is connected to conductor 618, is extended over the lower contact of cam 1034, right back contact of relay 930, upper right and lower left contacts of cam 928, left contacts of cam 1226, conductor 1233 to cams 1227 and 1211.

25 The sending of relay call indicator pulses takes place in substantially the same manner as disclosed in the above mentioned patent to A. E. Lundell et al., No. 1,464,084, and hence will not be discussed in detail herein.

30 As in the case of the above mentioned patent two light negative pulses are sent for each digit. In the case of the stations and thousands digits which are sent in positions 13 to 20 of the first revolution of switch 1200 the circuits for these pulses extend from battery through high resistance 1231, middle left front contact of relay 1220, lower right contact of cam 1227 to conductor 1233 and from ground at the upper left contact of cam 1006, conductor 1039, lower contact of cam 1229, right front contact of relay 1220, upper left contact of cam 1224 to conductor 1232. These negative impulses are modified in the usual manner by the interpolation of positive pulses and the addition of heavy negative pulses under the control of the registers 800^A. It is to be noted that rectangle 800^A represents the same set of registers as rectangle 800 of Fig. 6.

35 Switch 1210 is started out on its revolution by means of a circuit extending through its winding, lower left contact of cam 1218, left front contact of relay 1214, upper right and lower left contacts of cam 943, inner left back contact of relay 930, to ground at the outer left back contact of relay 936, which circuit is completed when relay 930 releases due to the response of the distant operator.

40 When sequence switch 1210 reaches position 17, the locking circuit of relay 1214 is opened and that relay releases, closing

5 at its back contact a circuit through the 65 winding of magnet 1210, upper left contact of cam 1218, outer left front contact of relay 1220, right back contact of relay 1214 to ground, which circuit is closed as soon as switch 1210 reaches position 1, to start the 70 switch on its second revolution. As soon as switch 1210 leaves position 2 in this second revolution the locking circuit of relay 1220 is opened and that relay releases. The 75 pulses for the hundreds, tens and units digits are transmitted to tip conductor 1232 over the right back contact of relay 1220 and the upper right contact of cam 1224, and to the ring conductor 1233, over the middle left back contact of relay 1220 and the lower 80 left contact of cam 1227. When switch 1210 reaches position 13 on its second revolution these paths are opened and, since relay 1220 is released, the paths formerly traced for the impulses are also open and hence no 85 pulses are sent out in positions 13 to 20 of the second revolution. Switch 1210 is started on the second half of its second revolution by means of a circuit from battery 90 through the winding of magnet 1210, upper right contact of cam 1218, right back contact of relay 1214 to ground. In positions 13 to 16 of the second revolution a circuit is closed for relay 1239 through its winding and the lower right and upper left 95 contacts of cam 1221, to ground at the back contact of relay 1214. The operation of relay 1239 closes a circuit from battery through the winding of the No. 0 counting 100 relay, upper contact of cam 941, front contact of relay 1239 to ground. The No. 0 counting relay operates and locks as usual through the windings of relays 902 and 915. When switch 1210 leaves position 16, relay 1239 releases permitting the operation of 105 relays 902 and 915 in the locking circuit of the No. 0 counting relay. Relay 915 closes a circuit from battery, winding of sequence 110 switch magnet 910, upper right contact of cam 924, inner right back contact of relay 918, front contact of relay 915 to ground, advancing sequence switch 910 to position 15 in which position the pulsing leads are 115 opened. Switch 910 is advanced to position 16 over the upper left contact of cam 920 to ground at the back contact of relay 603, in the manner previously described in connection with a call to a mechanical office. In position 16 relay 604 is operated opening 120 the circuit through the right winding of relay 603 to advance district selector 210. The district selector then initiates the disconnection of the sender in the same manner as described.

125 The operation of the timing switch of Fig. 5 to bring about the automatic restoration of the sender when the completion of a connection is unduly delayed or is prevented

by the abandonment of the call will now be discussed.

Wipe-out before registration.

- 5 It will be remembered that when the district selector is connected through to the sender, relay 702 was operated. The operation of relay 702 closes a circuit from battery, through the winding of relay 605, brush 614 of timing switch 600 in position 1, left back contact of relay 606, conductor 607, upper left contact of cam 1000, upper left contact of cam 1001, conductor 1002, outer right front contact of relay 702 to ground. 10 Relay 605 locks over its inner left front contact, to conductor 607. The operation of relay 605 prepares a circuit from battery through the right winding of relay 609, winding of relay 608, back contact of relay 609, brush 611 in positions 1 to 4, contact of interrupter 616, outer left front contact of relay 605 to ground, which circuit is completed as soon as interrupter 616 closes its contact. Relay 608 operates in this circuit 15 and locks from battery through the right winding of relay 609, winding of relay 608, left winding of relay 609, contact of relay 608, conductor 607, to ground. Relay 609 does not operate in this locking circuit as long as 20 the contact of interrupter 616 is closed, since it is shunted by the circuit thereover.
- When the interrupter 616 opens its contact relay 609 operates in the above traced locking circuit. When interrupter 616 again 25 closes its contact a circuit is completed from battery through the right winding of relay 609, inner front contact of relay 609, brush 611, in positions 1 to 4, contacts of interrupter 616, outer left front contact of relay 605, to ground. This circuit shunts the winding of relay 608 and causes that relay 30 to release. When interrupter 616 closes its contact, and relay 609 operates, a circuit is completed from battery, through the winding of stepping magnet 617, outer front contact of relay 609, brush 611 in positions 1 to 4, contact of interrupter 616, outer left front contact of relay 605 to ground. Magnet 617 attracts its armature in this circuit. 35 When interrupter 616 opens its contact relay 609 releases and magnet 617 releases to advance the brushes of switch 600 to position 2. With switch 600 in position 2 a circuit is closed from battery, through the winding of relay 606, inner right contact of relay 605, brush 612 in position 2, conductor 624, upper left contact of cam 1015 to ground. Relay 606 operates and closes a locking circuit 40 for itself through its winding and middle right contact to grounded conductor 607.
- Relay 606 closes a circuit from battery through the left winding of relay 625, inner right contact of relay 606, to grounded conductor 624. Relay 625 operates and closes 45 an obvious circuit for register 626. Relay 625 also closes a circuit from battery, through the winding of stepping magnet 617, contact of interrupter 627, brush 615 in positions 2 and 3, outer contact of relay 625 to ground. Switch 600 is advanced to position 3 and then to position 4 under the control of interrupter 627. 50 If the connection has been abandoned and the apparatus at office X released before any code pulses have been received, sequence 75 switch 210 will be in position 3 and sequence switches 910 and 1010 will not have left position 1. In this case relay 625 also closes a circuit from battery, winding of relay 604, left contact of cam 1037, left contacts of cam 946, inner contact of relay 625 to ground. The operation of relay 604 opens the circuit through the right winding of relay 603, and causes the release of relay 205 which is connected in this circuit at this time. 60 In the meantime the disconnection of the mechanical apparatus at office X opens the circuit of relay 201 and that relay releases in turn releasing relay 222. When switch 600 is moved to position 4 a circuit is completed from battery through the winding of relay 234, conductor 539, brush 517, outer right contact of relay 535, brush 527, brush 615 in position 4, outer contact of relay 625 to ground. Relay 234 operates and closes a circuit from battery through the winding of sequence switch magnet 210, upper contacts of cam 241, outer right front contact of relay 234 to ground. Sequence switch 210 is advanced to position 8 in this circuit. Since selector 200 has not been moved off normal, in position 8 a circuit is closed from battery, winding of magnet 210, lower right contact of cam 217, normal commutator segment 244, brush 287, lower left contact of cam 219 to ground, advancing switch 210 to position 9. When sequence switch 210 leaves position 3 70 the locking circuit of relay 207 is opened and that relay releases so that a circuit is closed in position 9 from battery winding of magnet 210, lower left contact of cam 224, inner left back contact of relay 207, upper left and lower right contact of cam 218, left contact of relay 205, upper contact of cam 213 to ground. Switch 210 is advanced to position 10 in this circuit. Switch 210 is advanced out of position 10 into position 15 in a circuit over the upper contacts of cam 241, outer right front contact of relay 234 to ground. Switch 210 is then advanced from position 15 to position 18 in a circuit over the upper right and lower left contacts of cam 241, left back contact of relay 205, lower contacts of cam 242, back contact of relay 222 to ground. It is advanced from position 18 to position 1 by means of a circuit through normal commutator segment 244. When switch 211 leaves position 13 ground is removed from conductor 528, releasing relays 518 and 519. The release of relay 518 re- 80 85 90 95 100 105 110 115 120 125 130

leases relay 502 which in turn releases relay 535, thus removing ground from conductor 602 and releasing relay 702.

Relay 702 opens the circuit of relay 701 causing it to release. It also removes ground from conductor 607, releasing relays 605 and 606. The release of relay 605 closes an obvious circuit for restoring switch 600 to normal. The release of relay 606 opens the circuit of relays 604 and 625.

If the district selector fails to open the circuit for relay 603, and relay 702 does not release, switch 600 is advanced from position 4 to position 5 under the control of relays 608 and 609 and interrupter 616.

In position 5 a circuit is closed for lamp 620 extending from battery through the lamp, brush 613 in position 5, inner left front contact of relay 606, conductor 621, outer left back contact of relay 703, right back contact of relay 710 to ground. Lamp 620 is lighted steadily in this circuit to indicate to the monitor operator which circuit has failed to release and the condition in which it failed. A circuit is also closed from ground at the outer left front contact of relay 606, over brush 614 in position 5 and the outer right contact of relay 605 to an auxiliary signal. The apparatus may then be released manually.

Wipe-out during registration.

If the mechanical apparatus at office X is disconnected during the time that pulses are being transmitted for registering the office code the operation is the same as just described except that the circuit of lamp 620 is extended over the front contact of relay 710 and interrupter 726, to ground so that lamp 620 flickers if the sender fails to release automatically. If the office code has been completed the operation of relay 716 causes sequence switch 1010 to move to position 2. When switch 1010 leaves position 1 the locking circuit of relay 605 opens and that relay releases advancing switch 600 to its next normal position. When switch 600 reaches normal, relay 605 reoperates and locks over conductor 607 to ground at the upper right contact of cam 1006 with switch 1010 in position 2, so that the sequence of operations described is restarted at that time.

When switch 1010 reaches position 2 a locking circuit is provided for relay 701 over conductor 729, upper left contact of cam 1006 to ground which is maintained through position 18 of switch 1010. Relays 609 and 608 operate to advance switch 600 to position 2 where relay 606 is operated to advance the switch to position 4 as before. When switch 600 reaches position 4 the circuit of relay 234 is closed in the manner described. When sequence switch 210 leaves position 13, relays 603 and 702 are released but relay 701 is held. With relay 702 re-

leased a circuit is completed from battery through the winding of sequence switch magnet 1010, upper left contact of cam 1017, left back contact of relay 702 to ground advancing sequence switch 1010 to position 16. 70 Switch 1010 is then advanced to position 17 over the lower left contact of cam 1017, right back contact of relay 1005, to ground. Switch 1010 is then advanced to position 1 over the upper left contact of cam 1004, conductor 1038, left contacts of cam 1211, upper left and lower right contacts of cam 943 to ground. As switch 1010 leaves position 4 ground is removed from conductor 607 and relays 605 and 606 are released to produce the release of the timing apparatus as previously described. When switch 1010 passes through position 5+10, 11+12 and 16+18 ground is again connected to conductor 607 permitting the operation of relay 605. 80 In the course of an automatic connection this provides means for timing the various operations so that if any one of them is unduly delayed the connection may be released or the operator apprised of the difficulty. During the restoration of switch 1010 relay 605 ordinarily does not remain operated long enough to cause the operation of the timing switch. Even if switch 600 should be advanced, when switch 1010 reaches position 1 relay 605 is released long enough to bring switch 600 to its next normal position. 90

Wipe-out during district selections.

If the apparatus at office X is disconnected during district selections switch 210 will be in position 4 to 8 and switch 1010 will be in position 13. With sequence switch 910 in position 2+4 the release of the apparatus at station X causes the release of relay 201 which in turn releases relay 222. With relay 222 released a circuit is closed from battery, winding of sequence switch magnet 210, upper right and lower left contacts of cam 242, right back contact of relay 222 to ground, advancing the sequence switch 210 to position 8. In position 8 the circuit of down-drive magnet 243 is completed over the lower contacts of cam 241, left back contact of relay 205, lower contacts of cam 242 to ground at the back contact of relay 222. Selector 200 is restored to normal under the control of magnet 243. 110

Sequence switch 210 is then advanced to normal in the manner previously described. The operation of the timing switch 600 is as described except that, due to the operation of relay 703 at the completion of registrations, the circuit of lamp 620 is extended to ground over the contact of interrupter 725, so that the lamp flashes to apprise the monitor of the circuit and the point at which it failed. Sequence switch 1010 is advanced to position 17 as previously described. 125

When sequence switch 1010 reaches posi- 130

tion 16 a circuit is completed from battery, winding of magnet 910, lower right contact of cam 920, upper left contact of cam 1029 to ground, in which circuit switch 910 is advanced to position 17. Switch 910 is advanced to position 18 over the upper left contact of cam 924, outer right back contact of relay 918 to ground and to position 1 over the circuit by which it was advanced to position 17. As soon as switch 910 reaches position 18 a circuit for advancing switch 1010 from position 17 to position 18 is closed over the upper contact of cam 921, whereupon switch 1010 is restored to normal as previously described.

Wipe-out after the completion of district group selection.

If the call is wiped out after the completion of district group selection, district selector sequence switch 210 will have left position 8, sequence switch 910 will be in position 6 or beyond and sequence switch 1010 will be in position 13 or beyond. Since switch 210 is advanced beyond position 8 the release of relays 201 and 222 is ineffective to cause immediate release of the district selector. Therefore, selections will be continued as for a normal call. The circuit for advancing sequence switch 210 under the control of relay 207 extends over the upper left and lower right contact of cam 218, left back contact of relay 205, right contact of cam 213 to ground instead of to ground at the front contact of relay 222. When switch 210 reaches position 15 with relay 222 released a circuit is closed through its winding, upper right and lower left contact of cam 241, left back contact of relay 205, lower contacts of cam 242, back contact of relay 222 to ground advancing sequence switch 210 to position 18 from whence it is advanced to normal as described. Switches 910 and 1010 will be restored as in a normal call.

Overflow.

If while district selector 200 is trunk hunting in position 9, no idle trunks are found the selector will come to rest on the overflow terminals of the group. The sleeve terminal of this set has no ground connected therewith and hence will be selected as an idle trunk. Relay 207 releases and advances sequence switch 210 to position 10. With selector 200 at an overflow position brush 229 will engage the overflow segment of commutator segment 228 and a circuit will be completed from battery winding of relay 234, left contacts of cam 247, commutator strip 228, brush 229, lower left contact of cam 219 to ground. Relay 234 operates and locks over its inner left front contact to ground at the front contact of relay 222. Relay 234 also connects battery and ground to the windings of relay 201 through inter-

rupters 245 and 246. As interrupters 245 and 246 close their upper and lower contacts, tone through coil 248 is intermittently applied to the line, to notify the subscriber that the call cannot be completed.

The operation of relay 234 also advances sequence switch 210 to position 16. When the subscriber hangs up in response to the tone, relays 201 and 222 release in turn releasing relay 234, advancing sequence switch 210 to position 18. Switch 200 is restored to position 18 and the sender is released in the usual manner.

Stuck sender.

If, for any reason, the sender does not complete its operation during the time permitted by the advance of switch 600 as previously described, the arrival of switch 600 in position 4 causes the operation of relay 604 and the release of relay 207, as above described, provided that relay has not already released due to the advance of the connection. When switch 600 reaches position 5 the previously traced circuit for relay 234 is completed. Relay 234 operates and advances switch 210 to position 8 as previously described. District selector 200 is then restored and sequence switch 210 is moved to position 9, in a circuit closed over normal commutator segment 244. Sequence switch 210 is advanced to position 10 over the back contact of relay 207 and the front contact of relay 222. It is then advanced to position 15 over cam 241 and the front contact of relay 234.

In the meantime the operation of relay 234 has connected tone to the subscriber's line through the windings of relay 201 as previously described. The release of the connection by the subscriber permits the restoration of the apparatus at office Y, as previously described.

Wipe-out-relay call indicator call.

It will be noted that the circuit for relay 625, which is also in part the normal energizing circuit of relay 606, is open at cam 1015, in position 14 of sequence switch 1010. This is the position occupied by that switch during relay call indicator operation. During a full mechanical call a substitute ground is furnished at cam 1242 and during certain parts of the relay call indicator operation over cam 947. This later ground is not closed in the positions of switch 910 during which pulses are sent out. Hence a call cannot be wiped out during that time. If, due to a delay in the response of the relay call indicator operator, relay 926 remains operated for an undue length of time, timing switch 600 is advanced under the control of relays 608 and 609 to position 4. In this position an energizing circuit is closed for relay 606 extending from battery through its

winding, inner right contact of relay 605, brush 612, in position 4, conductor 629, left contacts of cam 947, left contact of cam 1209, inner left front contact of relay 930, outer right back contact of relay 936 to ground. If key 628 is normal the call will be wiped out as previously described. However, if key 628 has been opened switch 600 will be advanced to position 5 under the control of 10 relays 608 and 609, which consumes a greater time than the advance under the control of interrupter 627. In position 5 lamp 620 will be flashed and the auxiliary signal operated so that the monitoring operator may 15 ascertain the cause of the delay and, if desirable, permit the wipe-out of the call by closing key 628. The purpose of key 628 is to delay the wipe-out of a relay call indicator call during light load periods when it 20 is possible that an operator may be delayed in responding to a call.

What is claimed is:

1. In a telephone exchange system, a calling line, a called line, selector switches, a 25 register sender for controlling said switches to establish a connection between said calling line and said called line, means in said sender for timing the various stages of the establishment of said connection, means for 30 restarting said timing means at the beginning of each of said stages of the connection, and means under the control of said timing means, operated when a stage of the connection requires an unusual length of time, 35 to release said sender and to signal an operator.

2. In a telephone exchange system, a calling line, a called line, selector switches, a 40 register sender for controlling said switches to establish a connection between said calling line and said called line, means in said sender for timing the various stages of the establishment of said connection, means for 45 restarting said timing means at the beginning of each of said stages of the connection, means under the control of said timing means, operated when a stage of the connection requires an unusual length of time, to release said sender, and means to indicate 50 to an operator at which stage of the connection the sender was released.

3. In a telephone exchange system, a calling line, a register sender, means under the 55 control of said register sender to extend said calling line to a called line in any one of a plurality of different types of offices, means in said sender for measuring a plurality of different periods of time, means for automatically releasing said sender at 60 the end of any one of said periods of time, and means for discriminating between the periods of time after which said releasing means shall become effective in accordance with the type of office in which the called 65 line is located.

4. In a telephone exchange system, a calling line, a register sender, means under the control of said register sender to extend said calling line to a called line in any one of a plurality of different types of offices, a timing switch, means for advancing said timing switch at different speeds to measure a plurality of different periods of time, means operated when said timing switch reaches a particular position to automatically release said sender, and means for differentiating between the means for advancing the timing switch in accordance with the type of office in which the called line is located. 70

5. In a telephone exchange system, a calling line, a register sender, means under the control of said register sender to extend said calling line to a called line by means of automatic switches or to an operator's position, 85 means in said sender actuated when the operation of said sender occupies more than a predetermined length of time to release said sender, and means to delay the release of said sender when said calling line is to be extended to an operator's position. 90

6. In a telephone exchange system, a calling line, selector switches, a register sender for controlling said switches to extend said calling line, means for completing connections between said extended calling line and called lines under the control of said sender either by other selector switches or by means of an operator, a timing switch, means operated when said switch advances to a particular position to cause the release of the sender, and means for delaying the advance of the timing switch to said position in the case of calls completed by means of an operator. 95

7. In a telephone exchange system, a calling line, selector switches, a register sender for controlling said switches to extend said calling line, means for completing connections between said extended calling line and called lines under the control of said sender either by other selector switches or by means of an operator, the extension and completion of said connections having a plurality of stages, a timing switch, means for restarting said timing switch at the beginning of each stage of a connection, means operated when said switch advances to a particular position to cause the release of the sender, and means for delaying the advance of the timing switch to said position in the case of calls completed by means of an operator. 100

8. In a telephone exchange system, a calling line, selector switches, a register sender, means in said sender for controlling said switches to extend said calling line to a called line or to an operator's position for extension to another called line, a timing switch in said sender, means for advancing 105

- said switch under the control of an interrupter to measure one period of time if said connection is to be completed by said selector switches, and means for advancing 5 said timing switch under the control of a pair of relays and an interrupter to measure a longer period of time if said connection is to be completed by means of said operator.
- 10 9. In a telephone exchange system, a calling line, selector switches, a register sender, means in said sender for controlling said switches to extend said calling line to a called line in any one of a plurality of different 50 types of offices, means for automatically releasing said sender after a predetermined period of time, and means to at will prevent said automatic release of the sender when the called line is located in a particular type 55 of office.
- 10 10. In a telephone exchange system, a calling line, selector switches, a register sender, means in said sender for controlling said switches to extend said calling lines to a called line in any one of a plurality of different offices, a timing switch, means to automatically release said sender when said timing switch reaches a particular position, and means to at will prevent said automatic release of the sender when said called line is located in a particular type 60 of office.
- 11 11. In a telephone exchange system, a calling line, selector switches, a register sender, means in said sender for controlling said switches to extend said calling lines to a called line in any one of a plurality of different offices, a timing switch, means to automatically release said sender when said timing switch reaches a particular position, and means to at will prevent said automatic release of the sender when said called line is located in a particular type 65 of office.
- 12 12. In a telephone exchange system, a calling line, selector switches, a register sender, means in said sender for controlling said switches to extend said calling lines to a called line in any one of a plurality of different offices, a timing switch, means to automatically release said sender when said timing switch reaches a particular position, and manually operable means for at will preventing said automatic release of the sender when said called line is located in a particular type 70 of office.
- 13 13. In a telephone exchange system, a calling line, selector switches, a register sender, means in said sender for controlling said switches to extend said calling line to a called line or to an operator's position for extension to another called line, a timing switch, means operated when said switch advances to a particular position to cause the release of the sender, means for delaying the advance of the timing switch to said 75 position in the case of calls completed by means of an operator, and means for at will preventing the automatic release of the sender in the case of calls to be completed by an operator.
- 14 14. In a telephone exchange system, a calling line, selector switches, a register sender, means in said sender for controlling said switches to extend said calling line to a called line or to an operator's position for extension to another called line, a timing switch, means for restarting said timing switch at the beginning of each stage of the extension of said calling line, means operated when said switch advances to a particular 80 position to cause the release of the sender, means for delaying the advance of the timing switch to said position in the case of calls completed by means of an operator, and means for at will preventing the automatic release of the sender in the case of calls to be completed by an operator.
- In witness whereof, I hereunto subscribe my name this 31st day of March, A. D. 1925.

OTTMAR H. KOPP.
